CLAIM

The ornamental design for a kitchen utensil drainage rack, as shown and described.

DESCRIPTION

FIG. 1 is a perspective view of my design of a kitchen utensil drainage rack as seen from the top and right sides;

FIG. 2 is a left side elevational view thereof;

FIG. 3 is a front elevational view thereof;

FIG. 4 is a top plan view thereof;

FIG. 5 is a rear elevational view thereof; and,

FIG. 6 is a bottom plan view thereof.

The broken lines showing a dish in FIG. 1, and a dish, spoon and glass in FIG. 3, are for illustrative purposes only and form no part of the claimed design.
